UNITED STATES PATENT OFFICE.

FRANCIS X. RESCH, OF WANETTE, OKLAHOMA.

BOAT.

Specification of Letters Patent. Patented Apr. 23, 1912.

1,024,419.

Application filed September 12, 1911. Serial No. 648,944.

To all whom it may concern:

Be it known that I, FRANCIS X. RESCH, a citizen of the United States, residing at Wanette, in the county of Pottawatomie and State of Oklahoma, have invented certain new and useful Improvements in Boats; and I do hereby declare the following to be a full, clear, and exact description of the invention, such as will enable others skilled in the art to which it appertains to make and use the same.

This invention relates to boats and is designed particularly to construct a means whereby the boat may be propelled, by the elimination of oars, and that the operator may face the bow of the boat during the movement thereof.

With the above and other objects in view, this invention consists in the construction, combination and arrangement of parts, wherein—

Figure 1 is a perspective view of a boat supplied with the propelling mechanism forming the subject matter of the present invention. Fig. 2 is a transverse section of a gunwale, illustrating one of the propelling mechanisms forming the subject matter of the present invention, parts thereof being in elevation. Fig. 3 is a section taken along line 3—3 of Fig. 2. Fig. 4 is a fragmentary top plan view of the gunwale illustrating the section thereof to which the propelling mechanism is attached.

The propelling mechanism forming the subject matter of the present invention comprises orificed plates secured to the gunwales of the boat coöperating with U-shaped clamps carrying inwardly projected lugs adapted to engage the orifices of said plates. These U-shaped clamps have rotatably mounted in the lower arms thereof, threaded clamping members which are adapted to engage the under side of said gunwales. A vertical standard is secured or formed to the upper arm of each U-shaped clamping member and has formed at its upper terminal, a bearing in which operates a shaft. A peculiarly formed paddle-wheel operates upon each shaft, said shafts being rotated, consequently the paddle-wheels being rotated by a train of gears operated by handles adjacent to the operator.

Reference being had more particularly to the drawings, A indicates a boat of any suitable and desired construction provided with the usual gunwale 10. Adjacent to

the seat which the operator is adapted to occupy an elongated plate 11 is secured to the upper surface of the gunwale, on each side of the boat, each plate being provided with the depressions 12 formed from the body of the plate. A bearing plate 13 is secured to the underside of the gunwale directly under each plate 11 and provides a bearing from the clamping member, as will hereinafter be more fully described. A U-shaped gunwale engaging member 14 is adapted to span or embrace the gunwale 10 and is provided on the interior of the upper horizontal arms 15 with the inwardly projecting lugs 16, which are adapted to engage the depressions 12 of the plates 11. The lower horizontal arm 17, of the U-shaped member 14 is provided with an interior threaded opening, in which the clamping member 18 is adapted to operate, said clamping member bearing against the plate 13 when the device is in its operative position. A U-shaped vertical standard 19 is secured to the upper horizontal arm 15 of each gunwale engaging member 14 and is provided at its upper terminal with a tapered outwardly extending bearing 20, a shaft 21 operates in this bearing and carries a hub 22 at its outer terminal. In order to provide a means whereby the rotation of the shaft will impart a forward or reverse movement to the boat a series of paddles or webs 23 are secured to each hub 22, through the instrumentality of the reduced extensions 24, which are adapted to be shrunk into or otherwise secured to the said hubs. A gear 25 is rigidly secured adjacent to the inner terminals of the shafts and between the arms of the U-shaped standard 19. This gear 25 meshes with a gear 26 mounted on the shaft 27, rotating within the bearing 28, said shaft terminating in a crank 29, located within the body or hull of the boat.

From the foregoing, it will readily be seen that by the peculiar construction of the gunwale, engaging member, it will be impossible for the same to move upon the gunwale, when the crank 29 is rotated. It will also be seen that by the provision of the gears 26 and 25, one rotation of the crank 29 will impart two revolutions to the paddle-wheels indicated generally as B. By the peculiar means whereby the blades 23 are secured to said hubs 22, it will readily be understood that should one or more blades

be broken the same may be removed and substitute blades secured to said hubs.

In order that the shafts may be firmly retained within the bearings 20 and be retained from reciprocation in said bearings a collar 30 is formed or otherwise secured to each shaft adjacent to the outer terminal of the coöperating bearing.

Having thus fully described my invention, 10 what I claim as new and desire to secure as Letters Patent is:—

In a boat propelling mechanism, the combination with a gunwale, of plates secured to the upper and lower sides of the said 15 gunwale, the plates secured to the upper side of said gunwales being provided with depressions, U-shaped gunwales engaging members adapted to span said gunwales, inwardly extending lugs carried by the upper 20 horizontal arms of said U-shaped gunwale engaging members, adapted to engage the

depressions of the plates aforesaid, clamping means carried by the lower horizontal arms of said gunwale engaging members, U-shaped vertical standards carried by the upper horizontal arms of said gunwale engaging members, outwardly extending bearings carried at the upper terminals of said standard, shafts rotating in said bearings, hubs carried at the outer terminals of said shafts, paddle blades detachably secured to said hubs, a train of gears operating between the vertical arms of said standards, and adapted to operate said shaft, and means whereby said gears may be rotated.

In testimony whereof I affix my signature in presence of two witnesses.

FRANCIS X. RESCH.
